(57) **CLAIM**

The ornamental design for a toilet footrest, as shown and described.

DESCRIPTION

FIG. 1 is a front perspective view of my design for a toilet footrest in an open position,

FIG. 2 is a front elevation view thereof,

FIG. 3 is a back elevation view thereof,

FIG. 4 is a left side view thereof, the right side being a mirror image thereof,

FIG. 5 is a top plan view thereof; and,

FIG. 6 is a front perspective view thereof in a closed position.

In the drawings, the broken lines are for the purpose of illustrating environment only and form no part of the claimed design.

1 Claim, 6 Drawing Sheets
